UNITED STATES PATENT OFFICE.

L'AIMÉE P. J. HERRING, OF LOS GATOS, CALIFORNIA.

DESIGN FOR A LADLE.

SPECIFICATION forming part of Design No. 34,649, dated June 11, 1901.

Application filed April 24, 1901. Serial No. 57,350. Term of patent 7 years.

To all whom it may concern:

Be it known that I, L'AIMÉE P. J. HERRING, a citizen of the United States, residing at Los Gatos, in the county of Santa Clara and State of California, have invented and produced a new and original Design for a Ladle; and I do hereby declare the following to be a full, clear, and exact description of the same, reference being had to the accompanying drawings, forming a part thereof.

Figure 1 of the drawings is a perspective view of a ladle illustrating my design; Fig. 2, a sectional view thereof, showing the handle partly broken away.

The leading feature of my design for ladles is the peculiar form of the body thereof, which is convex upon its exterior and gradually decreasing in depth and width from the point

b to the point c by the gradually-curved and unbroken edges a, said edges describing an arc of a circle. The body A has a neck B to form a spout, which is located at a right angle to the opening in the body and near the shallow portion thereof, and the handle C is secured to the side of the body.

Having now fully described my invention, what I claim as new, and desire to secure by Letters Patent, is—

The design for a ladle, substantially as herein shown and described.

In testimony whereof I affix my signature in presence of two witnesses.

L'AIMÉE P. J. HERRING.
